UNITED STATES PATENT OFFICE.

WILLIAM SYDNEY GRAHAM, OF CHICAGO, ILLINOIS, ASSIGNOR TO FEDERAL-HUBER COMPANY, OF CHICAGO, ILLINOIS, A CORPORATION OF ILLINOIS.

LAVATORY.

1,174,977.

Specification of Letters Patent. Patented Mar. 14, 1916.

Application filed June 7, 1909. Serial No. 500,561.

To all whom it may concern:

Be it known that I, WILLIAM S. GRAHAM, a citizen of the United States, and resident of Chicago, in the county of Cook and 5 State of Illinois, have invented certain new and useful Improvements in Lavatories, of which the following is a description, reference being had to the accompanying drawing, which forms a part of my specification. 10

My invention relates to lavatories and has for its object the provision of a simple and efficient construction wherein the inlet or service-pipe connecting member and the 15 outlet or waste connection is intended to be disposed beneath the basin top which may be seated or arranged beneath a slab or other frame work, and which is especially adapted for use in railway cars and the like 20 and known as dental lavatories.

In the drawing:—Figure 1 is a vertical sectional view taken through the inlet or service-pipe connecting portion. Fig. 2 is a horizontal sectional view taken on the line 25 2—2 of Fig. 1. Fig. 3 is a view similar to Fig. 1, illustrating a modified form. Fig. 4 is a horizontal sectional view taken on the line 4—4 of Fig. 3.

The bowl or main portion of the lavatory 30 A is bell shaped with flaring sides and a short vertical flange at the periphery. It is made of any suitable material, such as spun metal, and is provided with the outlet or waste-pipe connecting portion a, which is 35 shown provided with a perforated cap b; any suitable style of valve or stop plug being employed either within this member or at the point of its connection with the waste-pipe; but as this forms no part of my present 40 invention, further description thereof will not be necessary. The upper edge of the basin or body-portion A is provided with a rim c which may either be a separate piece and secured to the bowl portion in any suit- 45 able manner or be made integral therewith. This rim c comprises a flange curled upon itself, the curled edge being brought to within a short distance of the body of the bowl, leaving a narrow space or slit between 50 the curled rim and basin or body portion, as clearly shown in the drawing, thereby forming a chamber extending about the basin-top with which the service-pipe connecting portion d communicates by means of port e;

the volume and force of the water entering 55 through port e, being such as to force water throughout the greater portion of the chamber about the upper edge of the basin; the water passing through the narrow space or slit in the lower part of the chamber about 60 the basin-top, thus compelling the water to flow down the sides of the bowl or basin. The service-pipe connecting portion d is preferably made integral with the rim as shown. The rim c is also provided with an 65 opening f (see Fig. 1) which is placed opposite the direct passage-way or port g, of service-pipe connecting portion d. This port or opening f is so formed as to throw a jet 70 of water away from the wall of the basin and toward the center of the bowl as is evident from the construction, so that not only will the water pass from member or portion d into the rim-chamber through port e and into the basin, but also through port or 75 passageway g and out of port f into the basin. With this construction a jet of water is made to play into the basin, permitting the filling of a glass with water drawn from the same source of supply; passages e and g 80 being formed by walls c', g'.

Where it is desired to incase the lavatory as is generally done in railway-cars and the like, the rim c may be provided with the outwardly extending annular flange as at 85 c' which takes onto the slab or top member h of the cabinet or frame surrounding the lavatory, as shown in Fig. 1; or instead of the particular construction illustrated in Fig. 1, a construction similar to that shown 90 in Fig. 3 may be used wherein flange c' is given more of a curl as shown, thereby giving a finished appearance without the casing or cabinet.

In Fig. 3 I have illustrated a modified 95 form, wherein, instead of having passage or port g extend horizontally and into the chamber formed by rim c, the passage g is shown extending vertically. The passage or port g is to be so formed and extended as 100 to direct a jet of water into the basin or body-portion. I have illustrated the simplest manner of accomplishing this result, which consists in employing a separate tube or spout j which may either be screwed into 105 the passage or port g as shown or otherwise secured therein, and practically forms an extension of port or passage g. This spout

or pipe *j* is of course so formed as to throw the jet of water that passes therethrough, down into the basin as is evident from the construction. When this construction is employed it is not necessary to have port *f* in the rim *c*.

I have shown and described what I believe to be the simplest and best construction, but it is evident that the same may be altered without departing from the spirit of my invention.

Having thus described my invention, what I claim and wish to secure by Letters Patent is:—

15. 1. A lavatory comprising a bowl portion, a detachable rim adapted to direct the water uniformly down the sides of the bowl from adjacent the upper edge thereof, an inlet pipe formed integral with the rim, having two channels, one leading tangentially to the rim and the other channel lead-

ing radially through the rim into the bowl for the purpose specified.

2. A lavatory comprising a bowl having outwardly flaring sides and a vertical annular flange formed integral with the upper end thereof, a detachable rim having a central portion adapted to rest within said flange, inner and outer flanges formed integral with the said central portion and extending in substantially a horizontal direction, an inlet leading to the bowl, having a tangentially arranged channel leading to the rim whereby the water will be directed down the sides of the bowl from its upper edge and a radially extending channel leading from the inlet within the rim to the interior of the bowl for the purpose specified.

WILLIAM SYDNEY GRAHAM.
